FOREIGN PATENT DOCUMENTS

WO WO2019083651 5/2019

Primary Examiner — T Chase Nelson
Assistant Examiner — Sydney Margaret Parsley(57) **CLAIM**

The ornamental design for a swimming pool platform as shown and described.

DESCRIPTION

FIG. 1 is a front view of a swimming pool platform showing my new design;

FIG. 2 is a rear view of the swimming pool platform;
FIG. 3 is a right side view of the swimming pool platform;
FIG. 4 is a left side view of the swimming pool platform;
FIG. 5 is a top view of the swimming pool platform;
FIG. 6 is a bottom view of the swimming pool platform; and,
FIG. 7 is a top front side perspective view of the swimming pool platform.**1 Claim, 7 Drawing Sheets**(56)
